Patented May 16, 1967

207,652

REMOTE CONTROL FOR A TOY VEHICLE

Jesse D. Horowitz, 61 Jane St., New York, N.Y. 10014

Filed Mar. 31, 1966, Ser. No. 1,706

Term of patent 7 years

(Cl. D34—15)

FIG. 1

FIG. 2

FIG. 3

FIG. 4

FIG. 5

FIG. 6

FIG. 7

FIG. 1 is a plan view of a remote control for a toy vehicle, showing my new design;

FIG. 2 is a front view;

FIG. 3 is a bottom view;

FIG. 4 is a rear view;

FIG. 5 is a side view of the right of FIG. 4;

FIG. 6 is a side view of the left of FIG. 4;

FIG. 7 is a fragmentary sectional view taken on line 7-7 of FIG. 1.

The dominant features of my design reside in the full line portions shown.

I claim:

The ornamental design for a remote control for a toy vehicle, substantially as shown and described.
